(57) **CLAIM**

The ornamental design for a carry bag, as shown and described.

DESCRIPTION

FIG. 1 is a perspective view of a carry bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the carry bag where the carry bag is in a close state;

FIG. 10 is a left side elevational view thereof;

FIG. 11 is a cross sectional view taken along line 11-11 shown in FIG. 10; and,

FIG. 12 is an enlarged view of portion 12 shown in FIG. 1. The thin long even-spaced broken lines in the drawings depict zippers of the carry bag that form no part of the claimed design. The thick short even-spaced broken lines in the drawings depict stitching that form no part of the claimed design.
